UNITED STATES PATENT OFFICE

JOHN RIGBY, OF NEW BEDFORD, MASSACHUSETTS

NOZZLE

Application filed January 28, 1932. Serial No. 589,457.

This invention relates to nozzles, and more particularly to an improved nozzle construction which can be readily mounted on any type of container such as cardboard or the like so as to facilitate the pouring of the dry material within the container.

An object of this invention is to provide an improved nozzle construction which embodies features whereby it may be readily mounted on any container of a cardboard, heavy paper or material of flexible construction so that the material in the form of powder or granular particles may be readily poured out of the container without undue spilling thereof.

Another object of this invention is to provide a device of this kind which is so constructed that it will prevent the contents of the container from becoming dirty after it has once been opened.

The above and various other objects and advantages of this invention will in part be described in and in part be understood from the following detailed description of the present preferred embodiment, the same being illustrated in the accompanying drawing wherein:

Figure 1 is a detail perspective view of a device constructed according to the preferred embodiment of this invention mounted on a box or container which is shown in fragmentary form;

Figure 2 is a vertical section taken substantially through the center of the device and showing the box in fragmentary sectional form;

Figure 3 is a bottom plan view of the device.

Referring to the drawing wherein like characters of reference designate corresponding parts throughout the several views, the letter C designates generally a container of conventional construction such as cardboard, heavy paper or other relatively flexible material which is adapted to receive a material in powdered or granular form.

At the present time, when it is desired to remove the loose material from the container C, a hole is formed in the container or the entire top is loosened and the material poured

out therefrom. Through this procedure, however, a quantity of dirt or the like is permitted to enter the container and it is in order to prevent the contents of the container C from becoming contaminated by dirt or the like that I have provided a pouring nozzle, generally designated as N, which comprises an L-shaped base plate 10 having one leg 11 thereof disposed along the outer vertical side of the container C and the other leg 12 disposed on the top of the container C. The opposite ends of the base plate 10 are preferably turned over, as at 14, so as to provide a blunt edge and this turned over portion 14 is also bent outwardly a slight degree so as to facilitate the positioning and removal of the device on the container C. The nozzle N is of tapering construction and is disposed on an obtuse angle to the upper leg 12 of the base 10 and the leg 12 is provided with an opening 13 therethrough communicating with the nozzle 10. The container C may be provided with an opening or hole 15 which can be cut through the upper wall thereof by any suitable means and the pouring means herein disclosed is then disposed over this opening 15 and the width of the plate or leg 12 is such as to extend beyond the marginal edges of the opening 15.

A spring or clamping member 16 has one end thereof secured to the base plate member 12 and the opposite end thereof is free and extends toward the free end of the base plate member 12 and if desired may extend beyond the free edge thereof as shown in Figures 2 and 3. This clamping member provides means whereby the base plate 12 may be held in a position overlying the opening 15 in the container C. The front or vertical plate member 11 is provided with an inwardly extending tang 17 which is formed with the returned edge portion 14 and extends in a direction parallel to the upper plate member 12. This tang 17 is adapted to pierce the side wall of the container C and when so disposed will prevent upward movement of the front portion of the plate 10 so that the nozzle N will not drop off of the container C as it is tilted to pour the material out through the nozzle. As shown in Figure

2, the clamp or spring member 16 engages the lower surface of the top of the container C and clamps the base plate member 12 against vertical movement relative to the 5 top of the container but permits lateral movement thereof in the event it is desired to remove the device from the container.

In the use of this device, the container C may be provided with a hole or opening 15 10 in the top thereof at any desired point along the top and the free end portion of the spring 16 may then be inserted in this opening 15 and the device moved in a horizontal direction so that the front plate member 11 will 15 lie against the side wall of the container C. In this position, the securing tang 17 will pierce the front or side wall of the container C and the device will then be firmly held against relative movement on the container 20 er which can be reverted to pour the material out through the opening 15 and the nozzle N.

It is, of course, understood that various changes and modifications may be made in the details of construction and design of 25 the above specifically described and embodiment of this invention without departing from the spirit thereof, such changes and modifications being restricted only by the scope of the following claims.

30 What is claimed is:—

1. A pouring means adapted to removably engage about the corner of two angular related face portions of a receptacle comprising an L-shaped base plate, upturned 35 end portions formed with each free end of said plate, a nozzle secured to one leg of said plate, and clamping means carried by one plate and engaging one wall of the receptacle on the inner face thereof to hold 40 the plate against lateral movement relative to said one wall.

2. A pouring means comprising a base plate of substantially L-shaped construction, a nozzle secured to one leg of said 45 plate, upturned end portions formed with each leg of said plate, a resilient clamp carried by one leg and adapted to resiliently clamp one wall of the container between said one leg and the clamp, and means carried by 50 the other leg cooperating with said clamp to removably secure the plate on the container.

In testimony whereof I hereunto affix my signature.

JOHN RIGBY.
